(57) **CLAIM**

The ornamental design for an interchangeable/wearable hinged display device assembly, as shown and described.

DESCRIPTION

This application is also related to co-pending and co-owned U.S. application Ser. No. 29/494,817, entitled Wearable Hinged Display Device, filed on Jun. 24, 2014, U.S. application Ser. No. 29/494,823, entitled Wearable Hinged Display Device, filed on Jun. 24, 2014, and U.S. application Ser. No. 29/495,221, entitled Interchangeable Eyewear Assembly, filed on Jun. 27, 2014, the disclosures all of which are incorporated herein by reference.

FIG. 1 is a front perspective view of a component of an interchangeable/wearable hinged display device assembly according to an embodiment of our design in an open position;

FIG. 2 is a front elevation view of the component of the interchangeable/wearable hinged display device assembly of FIG. 1;

FIG. 3 is a back elevation view of the component of the interchangeable/wearable hinged display device assembly of FIG. 1;

FIG. 4 is a right elevation view of the component of the interchangeable/wearable hinged display device assembly of FIG. 1;

FIG. 5 is a left elevation view of the component of the interchangeable/wearable hinged display device assembly of FIG. 1;

FIG. 6 is a top elevation view of the component of the interchangeable/wearable hinged display device assembly of FIG. 1;

(Continued)

FIG. 7 is a bottom elevation view of the component of the interchangeable/wearable hinged display device assembly of FIG. 1;

FIG. 8 is another front perspective view of the component of the interchangeable/wearable hinged display device assembly of FIG. 1;

FIG. 9 is a front perspective view of a component of an interchangeable/wearable hinged display device assembly according to the embodiment of our design in a closed position;

FIG. 10 is a front elevation view of the component of the interchangeable/wearable hinged display device assembly of FIG. 9;

FIG. 11 is a back elevation view of the component of the interchangeable/wearable hinged display device assembly of FIG. 9;

FIG. 12 is a right elevation view of the component of the interchangeable/wearable hinged display device assembly of FIG. 9;

FIG. 13 is a left elevation view of the component of the interchangeable/wearable hinged display device assembly of FIG. 9;

FIG. 14 is a top elevation view of the component of the interchangeable/wearable hinged display device assembly of FIG. 9;

FIG. 15 is a bottom elevation view of the component of the interchangeable/wearable hinged display device assembly of FIG. 9; and,

FIG. 16 is a rear perspective view of the component of the interchangeable/wearable hinged display device assembly of FIG. 9.

Broken lines are environmental only and form no part of the claimed design.
